(57) **CLAIM**

The ornamental design for an adaptor for point of care testing cartridge, as shown and described.

DESCRIPTION

FIG. 1 is a perspective view of an adaptor for point of care testing cartridge in accordance with our design;

FIG. 2 is a front elevational view thereof;

FIG. 3 is a side elevational view thereof, with the opposite side elevational view, the top view and the bottom view being substantially identical;

FIG. 4 is a rear elevational view thereof; and,

FIG. 5 is a cross-sectional view taken along line 5—5 of FIG. 2.
